UNITED STATES PATENT OFFICE

106,891

DESIGN FOR A REFRIGERATOR DISPLAY CABINET

George J. Hopkins, Kendallville, Ind., assignor to McCray Refrigerator Company, Kendallville, Ind., a corporation of Indiana

Application August 4, 1937, Serial No. 70,843

Term of patent 7 years

To all whom it may concern:

Be it known that I, George J. Hopkins, a citizen of the United States, residing at Kendallville, in the county of Noble and State of Indiana, have invented a new, original, and ornamental Design for a Refrigerator Display Cabinet, of which the following is a specification, reference being had to the accompanying drawing, forming a part thereof, in which:

The figure is a front perspective view of a refrigerator display cabinet showing my new de-

sign, the distinguishing, essential and dominant features or characteristics of the design being the base, marginal edges and decorative stripings which are of a different color than the remaining portion of the cabinet and which are all shown in black in the drawing. The rear surface of the cabinet is plain and of conventional type.

I claim:

The ornamental design for a refrigerator display cabinet as shown and described.

GEORGE J. HOPKINS.
